HOLDING APPLIANCE FOR NURSING BOTTLES

Frank L. Stretz, Kansas City, Mo., assignor to
Robert O. Meyer, Kansas City, Mo.

Application December 29, 1945, Serial No. 638,209

5 Claims. (Cl. 248—104)

1

This invention relates to nursing bottle supports in the nature of a holding appliance for such bottles that is capable of mounting the same upon a convenient support and in proximity to the infant's mouth where the nipple of the bottle may be engaged and released at will.

The primary object of this invention is to provide a holding appliance for nursing bottles that is capable of maintaining the bottle in a selected normal position with respect to the infant using the same and further having the property of easily yielding to the pull that might be exerted thereon when the infant reaches for the bottle and pulls the same toward an inclined nursing condition where the bottle is disposed at an angle with the nipple in a lowered position.

Further aims of the invention include the specific manner in which the several cords of the apparatus are related and disposed with respect to the cradle having the bottle therein and the unique way in which the said cords are capable of moving the bottle to a normal position with its longitudinal axis on substantially a horizontal plane.

Further objects of the invention include the unique and effective way in which the cradle for the bottle is held in engagement therewith and tightened as downward pull is exerted, all to the end that the bottle will not accidentally slip from the assembled position as it is shifted from the nursing to the inoperative condition.

Further aims of the invention will appear during the course of the following specification referring to the accompanying drawing, wherein:

Fig. 1 is a top plan view of a holding appliance for nursing bottles made in accordance with the present invention and showing the same mounted upon a conventional baby crib.

Fig. 2 is an edge elevational view of the appliance.

Fig. 3 is a perspective fragmentary view of the holding appliance per se; and

Fig. 4 is a fragmentary detailed sectional view taken on line IV—IV of Fig. 3.

The form of the invention chosen for illustration and shown in the accompanying drawing comprises a cradle 10 formed of an initially flat piece of flexible material such as fabric, the marginal edges whereof are provided with openings 12 for the purpose hereinafter more fully set down. These openings 12 are provided at spaced intervals along proximal marginal edges of cradle 10 that are in spaced relation when the nursing bottle 14 is supported.

A number of specially positioned cords are em-

2

ployed to not only hold the cradle assembled against bottle 14 but to suspend the cradle and its bottle in a manner shown in Figs. 1 and 2. One cord extends to each side respectively of cradle 10 and from a point near the top of cradle 10 after it has been passed through certain of openings 12. The cords which extend to each side of cradle 10 are substantially identical in that each is U-shaped and includes legs 16 and a bight 18. It is the bight portion of the U-shaped cords that is threaded through certain of openings 12 to form a tubular cradle capable of receiving the bottle 14. When such a cradle is used, the material from which cradle 10 is made will assist in keeping the bottle warm during the feeding period and if feeding bottles of different contours are moved into place in cradle 10, it will immediately adjust itself thereto to prevent accidental displacement.

The cradle is soft and therefore will not break the bottle 14 and since no slippage can occur due to the lacing, a factor of safety is always present. The edges adjacent to holes 12 are always spaced apart and as a downward pull is exerted upon bottle 14, cords on each side thereof at the top will tighten and prevent removal from its normal place within cradle 10.

The free ends of legs 16 of the two cords are connected to a separator 20 in the form of a short piece of rigid material and a satisfactory way of interconnecting the ends of legs 16 and separators 20 is to grip the separators, pass the legs 16 through the bore and then knot the ends. The knots 22 are withdrawn into a counter-bore 24 to aid in the appearance and prevent unauthorized manipulation thereof. The length of separators 20 is substantially the same as the length of cradle 10 and legs 16 of the cords are in parallelism.

The separators 20 are attached to a suitable support such as the side rails 26 of a baby crib and the attachment to these side rails 26 is affected by another substantially U-shaped cord taken from separator 20. These cords each have legs 28 extending through bores 30 in separators 20 and the bight 32 holds a clip 34 which bridges legs 28 after parts of the legs are wrapped around the rail of support 26 as illustrated in Figs. 1 and 2. A quick mode of attachment is thereby presented and while the legs 28 are substantially parallel and slightly spaced apart, they prevent rotation of bottle 14 about an axis extending transversely of the points of support and cooperate with legs 16 in holding the bottle to a normal horizontal position when the infant has released

the same. This immediate swinging to an inoperative position will prevent objectionable leaking through the holes in the nipple of bottle 14 and where it becomes necessary to feed infants water during the night, the holding appliance may be affixed in place upon retiring to render the same available at any hour of the night by the infant should it awaken and reach for the bottle 14.

All component parts of the holding appliance are washable and easily cleaned to maintain a sanitary condition.

The manner of suspending bottle 14 from the side rails 26 of the crib may be altered by shortening legs 28 of the cords bridging the distance between separators 20 and the point of support. It is unnecessary to tie knots in any of the cords when mounting the appliance for use and speedy removal from the crib side rails is possible if such becomes necessary.

It is realized that appliances having physical characteristics different from those shown and described may be made without departing from the spirit of the invention and therefore, it is desired to be limited only by the scope of the appended claims.

Having thus described the invention, what I claim as new and desire to secure by Letters Patent is:

1. A holder for a nursing bottle comprising a cradle for the bottle; and a plurality of cords extending laterally from the cradle to points of support on each side thereof, said cradle being an initially flat piece of flexible material wrapped around the bottle, said cords serving to lace together the ends of the material, said cords each being separably passed through openings formed in the proximal marginal edges of the material and freely slidably therein whereby force applied to the bottle having a tendency to pull the cords will draw the material tighter about the bottle.

2. A holder for a nursing bottle comprising a cradle for the bottle formed of an initially flat piece of flexible material having openings in the marginal proximal edges of the material when the same is wrapped around the bottle; a substantially U-shaped cord having the bight thereof loosely laced through certain of the said holes and the legs extending laterally to one side of the cradle; and another substantially U-shaped cord having the bight thereof loosely laced through certain of the said holes and the legs extending laterally to the opposite side of the cradle, the said legs of both U-shaped cords being spaced apart and in substantial alignment, said cords drawing together the said marginal edges of the cradle when outward force away from the cradle is exerted upon the legs of said cords.

3. A holder for a nursing bottle comprising a cradle for the bottle formed of an initially flat piece of flexible material having openings in the marginal proximal edges of the material when the same is wrapped around the bottle; a substantially U-shaped cord having the bight thereof laced through certain of the said holes and the legs extending laterally to one side of the cradle; another substantially U-shaped cord having the bight thereof laced through certain of the said holes and the legs extending laterally to the opposite side of the cradle, the said legs of both

U-shaped cords being spaced apart and in substantial alignment; a separator joining the ends of each U-shaped cord to hold legs thereof in spaced apart, substantially parallel relation; and means for attaching each of the separators respectively to a support.

4. A holder for a nursing bottle comprising a cradle for the bottle formed of an initially flat piece of flexible material having openings in the marginal proximal edges of the material when the same is wrapped around the bottle; a substantially U-shaped cord having the bight thereof laced through certain of the said holes and the legs extending laterally to one side of the cradle; another substantially U-shaped cord having the bight thereof laced through certain of the said holes and the legs extending laterally to the opposite side of the cradle, the said legs of both U-shaped cords being spaced apart and in substantial alignment; a separator joining the ends of each U-shaped cord to hold legs thereof in spaced apart, substantially parallel relation; and means for attaching each of the separators respectively to a support, the attaching means being joined to the separators at a point between the points of juncture between the respective separator and the said U-shaped cords.

5. A holder for a nursing bottle comprising a cradle for the bottle formed of an initially flat piece of flexible material having openings in the marginal proximal edges of the material when the same is wrapped around the bottle; a substantially U-shaped cord having the bight thereof laced through certain of the said holes and the legs extending laterally to one side of the cradle; another substantially U-shaped cord having the bight thereof laced through certain of the said holes and the legs extending laterally to the opposite side of the cradle, the said legs of both U-shaped cords being spaced apart and in substantial alignment; a separator joining the ends of each U-shaped cord to hold legs thereof in spaced apart, substantially parallel relation; and means for attaching each of the separators respectively to a support, the attaching means being joined to the separators at a point between the points of juncture between the respective separator and the said U-shaped cords, said attaching means each comprising a U-shaped cord having the ends thereof anchored to the separator and a clip on the cord at the bight thereof for bridging the legs of the U-shaped cord after the same have been wrapped about a support.
